D. DEMEULE,
PROTECTOR ROD HOLDER FOR LOOMS,
APPLICATION FILED AUG. 15, 1918.
1,831,626.

Patented Feb. 24, 1920.

FIG. 1.

FIG. 4.

FIG. 2.

FIG. 3.

INVENTOR:

Dorila Demeule

By Heard Smith & Tenant

ATTORNEY:

UNITED STATES PATENT OFFICE.

DORILA DEMEULE, OF MANCHESTER, NEW HAMPSHIRE, ASSIGNOR TO DRAPER CORPORATION, OF HOPEDALE, MASSACHUSETTS, A CORPORATION OF MAINE.

PROTECTOR-ROD HOLDER FOR LOOMS.

1,331,626.

Specification of Letters Patent.

Patented Feb. 24, 1920.

Application filed August 15, 1918. Serial No. 250,052.

To all whom it may concern:

Be it known that I, DORILA DEMEULE, a citizen of the United States, and resident of Manchester, county of Hillsborough,

5 State of New Hampshire, have invented an Improvement in Protector-Rod Holders for Looms, of which the following description, in connection with the accompanying drawing, is a specification, like characters on the

10 drawing representing like parts.

This invention relates to journal brackets for looms and the object thereof is to provide a journal bracket of a character which may be secured firmly to a part of the loom

15 and which will not become loosened and disengaged by the vibration of the loom or the part to which the bracket is attached.

More specifically the invention comprises improvements in brackets for supporting the

20 protector rod of the loom from the lay. The brackets which have been heretofore generally used for supporting the protector rods from the lay have comprised L-shaped plates having downwardly extending bosses

25 providing journals for the protector shaft, said L-shaped plates being secured to the lay by screws extending into the back face and bottom of the lay respectively.

The vibration of the lay and the shock 30 caused by the operation of the protector mechanism in time loosens the screws which thus attach the bracket to the lay and render the support for the protector shaft inoperative. The present invention contemplates

35 the production of a journal bracket for the protector rod of a loom which can be so securely fastened to the lay that it will not be loosened by the vibration of the lay or the shock occasioned by the operation of the

40 protector mechanism.

This is accomplished in the preferred embodiment of the invention disclosed herein by providing a bracket comprising two members, one of L-shaped form adapted to fit one face and bottom of the lay and having a downwardly extending boss providing a journal for the protector rod and a second member hinged to the free edge of the portion of the L-shaped member which en-

45 engages the bottom of the lay, said hinged member being adapted to engage the opposite face of the lay. The bracket formed by these members is secured to the lay by a bolt passing through the lay and the members

of the bracket which engage the faces of 55 the lay and the nut on the bolt locked so that it cannot be unscrewed by shock or vibration.

It will be understood that while the invention herein disclosed is particularly applicable to journal brackets for supporting the protecting rods of looms it is capable of use in other relations.

A further feature of the invention consists in providing a journal bracket of the 65 class described with means for anchoring the end of a spring for controlling the action of the protector rod.

Other features of the invention will more fully appear from the following description 70 and the accompanying drawings and will be pointed out in the annexed claims.

The drawings illustrate my invention as applied to the lay of a loom of the usual Northrop type.

In the drawings;

Figure 1 is an elevation of the rear side of the lay of a loom showing a portion of one of the swords for supporting the same and a protector rod journaled in a journal 80 bracket embodying my invention,

Fig. 2 is a detail view of the rear portion of a lay showing the manner in which the journal bracket for the protector rod is secured to the lay,

Fig. 3 is a transverse sectional view through the lay showing the journal bracket for the protecting rod bolted to the lay, and

Fig. 4 is a detail view on line 4-4, Fig. 3, showing the downwardly extending jour- 90 nal in central vertical section.

Inasmuch as the preferred embodiment of the invention is disclosed as applied to the journal brackets for supporting the protector rod of a loom only a sufficient portion 95 of the loom is illustrated as is necessary to show the application of the present invention thereto. It will be understood that the portion of the loom so illustrated herein comprises the usual parts of the well known 100 Northrop automatic filling replenishing loom.

As illustrated in Fig. 1 the usual lay 1 which is carried by the sword 2 terminates in a shuttle box 3 having a rear binder 4 105 which is engaged by the arm 5 of the protector mechanism, said arm 5 being secured to the offset end 6 of the protector rod 7

which may be mounted in suitable journals carried by the sword 2 and in one or more other journal brackets 8 secured to the lay of the loom.

5 The present invention comprises a journal bracket consisting of two members one of which is an L-shaped plate having a base portion 9 adapted to engage the bottom of the lay and a vertical portion 10 extending 10 upwardly therefrom adapted to fit the back face of the lay.

A downwardly extending boss 11 is apertured to form a journal 12 for the protector shaft 7. The downwardly extending boss 15 is also provided with a groove or recess 13 adapted to receive and anchor the end of the helical spring 14 which controls the movement of the protector rod, the opposite end of the spring 14 being anchored in a collar 20 15 which is secured to the protector rod 7 by a set screw 16.

The free edge of the bottom portion of the L-shaped member is provided with a boss 17 adapted to receive the pin 18 forming a pintle upon which the other member of the bracket is mounted.

The other member of the bracket comprises a plate 19 having at its lower end bosses 20, which are apertured to receive the 30 pintle 18 so that in effect the member 19 of the bracket is hinged to the free lower edge of the L-shaped plate which engages the bottom and back of the lay.

The portion 10 of the L-shaped member 35 is provided at a desirable distance above the bottom with an aperture 21 which may be provided with a countersink 22 to receive the head of the bolt 23, said bolt passing through the vertical portion 10 of the L-shaped member, entirely through the lay 40 in parallelism with the bottom thereof and through a vertical slot 24 in the hinged member of the bracket. The bolt 23 is provided with the usual nut 25 which may be secured from withdrawal in any suitable 45 manner, as for example, by a cotter pin 26 passing through the bolt adjacent the outer face of the nut.

By reason of this construction the journal

bracket is so securely fastened to the lay 50 that it cannot be loosened either by the vibration of the lay or by the shock imparted when the dagger carried by the protector rod engages and operates the usual mechanism for knocking off the loom. 55

It will be understood that the embodiment of the invention disclosed herein is illustrative and that various changes in form, arrangement and construction of parts may be made within the meaning and 60 scope of the following claims.

Having thus described my invention what I claim as new and desire to secure by Letters Patent is:

1. In a loom comprising a lay having a 65 protector rod extending along the same, means for supporting said protector rod including a bracket having an L-shaped member engaging one face and the bottom of said lay and a member hinged to the lower 70 free edge of said L-shaped member engaging the opposite face of said lay and a bolt passing through said lay and the members of said bracket which engage said opposite faces of the lay, thereby securing the bracket 75 firmly to said lay.

2. In a loom comprising a lay and having protecting mechanism including a protector rod extending along the bottom of said lay, a journal bracket for said protector 80 rod comprising an L-shaped member adapted to embrace and fit one face and the bottom of said lay and a member hinged to the lower free edge of said L-shaped member 85 engaging the other face of said lay, a bolt passing through said lay from face to face and through both face engaging members of said bracket, the bearing for said protector rod comprising a boss formed integral with said L-shaped member and depending therefrom and having a recess to provide an anchorage for a helical spring encircling said protector rod and anchored at its opposite end to a suitable collar secured to said rod. 90

In testimony whereof, I have signed my name to this specification.

DORILA DEMEULE.
